CONTAINER HANDLE

Filed Feb. 21, 1931

Charles V. Brady,
Inventor.
Deler J. Haynes,
Attorney.

UNITED STATES PATENT OFFICE

CHARLES V. BRADY, OF ST. LOUIS, MISSOURI, ASSIGNOR TO BEMIS BRO. BAG COMPANY, OF ST. LOUIS, MISSOURI, A CORPORATION OF MISSOURI

CONTAINER HANDLE

Application filed February 21, 1931. Serial No. 517,400.

This invention relates to handles, and with regard to certain more specific features, to handles formed from strip fabric used on and to seam containers made from fabric and the like.

Among the several objects of the invention may be noted the provision of strong, flexible means on containers for providing a manual purchase, which means shall not be subject to tearing or excessive deterioration during ordinary handling; and the provision of means of the class described which shall be easily and economically manufactured and applied. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

In the accompanying drawing, in which is illustrated several of various possible embodiments of the invention,

Fig. 1 is a perspective view of a partially folded bag or container showing the application of the invention thereto, with one part shown open for purposes of description; and, Fig. 2 is a plan view similar to the bag shown in Fig. 1, showing the bag closed and filled with material.

Similar reference characters indicate corresponding parts throughout the several views of the drawing.

In the ordinary handling of filled containers such as the bag shown in Figs. 1 and 2, the workmen or handler experiences difficulty in obtaining a hold on the bag sufficient to lift the same without the use of hooks or the like. The use of hooks tears the fabric, thereby allowing bagged material to leak out. Furthermore, their use may render the bag unfit for further service. To overcome this difficulty, I provide strips or handles extending from the bag as shown in Figs. 1 and 2, which broadly, are formed by extending a fastening strip comprising a seam beyond the edge of a container.

Referring now more particularly to Fig. 1

there is shown at numeral 1 a container or bag formed from fabric 2 or the like, the longitudinal edges of the fabric 2 being juxtaposed and preferably joined in a lapped seam as shown at numeral 3. One end of the container or bag 1, the mouth, is left open as shown at numeral 5 to receive material to be bagged, and the other end 7 is closed by a strip 9.

The lapped joint or seam 3 may be formed as described in my United States Patent No. 1,853,013, granted April 5, 1932, to provide a joint with an efficiency which may be greater than 100%; that is, the strength of the joint may be greater than the strength of the material which forms it. As further described in the above-mentioned patent application, the joint 3 may be formed, if the outer material 2 is unlined, by overlapping the edges and applying a layer of cement or adhesive material 11, comprising preferably process rubber, gum, latex, asphalt or any adhesive having the proper qualities.

The seam 3 is described only for the sake of clarity and may be a sewed seam or of any other desired construction, and may be positioned at any other part of the bag 1. The bag preferably comprises fabric such as burlap or the like but may comprise other material.

The edge 7, and in this case the bottom edge of the bag or container 1, is sealed by a joint or seam such as is described in detail in my said Patent No. 1,853,013. Briefly this joint comprises a strip of material, or closure means 9, to one side of which is applied, prior to the application to the bag, a layer of the adhesive material 11.

After application of the cement 11, to the strip 9, but before the cement dries, the strip 9 is folded on itself along a longitudinal crease 8 with the cement 11 located on the inner surfaces of the strip. As the strip 9 is thus folded, juxtaposed edges 13 and 15 of the edge 7 of the bag 1, are included between the surfaces of the strip 9. Fig. 1 clearly shows the arrangement at the portion of the parts laid open. It is preferable that after, or at the time of applying the folded strip 9 to the juxtaposed edges 13 and 15 that

the strip 9 be compressed and creased, either by rollers or otherwise, so that the cement 11 is forced into the fibres of the fabric 2 and so that the seam is made thin.

- 5 Ends 17 of the strips 9 are allowed to extend substantially beyond the edges of the bag 1 and as shown in Fig. 1, these ends 17 may also be folded along the crease 8 with cement 11 spread between the juxtaposed surfaces. These extended ends 17 are then doubled back or looped as at 18 to form the handles of the bag or container. Rivets 19 hold the loops 18 closed and prevent the strip 9 from being pulled from the container when 15 the handles or loops 17 are used to lift the bag 1. In some instances the rivets may be omitted as for instance, when the strip 9 is sewed on, extra stitches may be provided at the points of joining; or any other suitable 20 used means may be eliminated.

The strips 9 may be cut from any kind of fabric as for instance, from that which comprises the outer layer of the fabric 2, or, the strips 9 may be selected of a stronger material 25 than the fabric 2, thereby providing stronger handles 17.

In use the workman may insert his hand into the loops or handles 18 and thereby obtain a secure hold. The loop handles 18 may 30 also be grasped as a whole, and if such is the case, an unusually strong and easily gripped lifting handle is provided.

As shown in Fig. 2 a strip 23, similar to the strip 9, is used to seal the mouth 5, of the 35 bag 1, after the container 1 is filled. Other known methods, however, may be used to seal the mouth 5, sewing them together.

It is to be noted that the number of handles formed on the bag may be varied. Thus 40 only one end of the strip 9 may be extended and looped back in the manner described. Or, the ends of the strip 23 (if such a strip is used to seal the mouth) may be extended, whereby, as many as four handles may be 45 formed from the two strips 9 and 23.

An advantage of the invention is that the same strip or means, which is provided to seal the end or to provide a seam for the end of a container or bag, is also utilized to 50 provide a strong lifting handle, whereby a workman can easily obtain a good purchase on the bag or container. In this way, the necessity for the use of hooks or the like, on bags is overcome.

55 In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing shall be interpreted as illustrative and not in a limiting sense.

I claim:

1. A bag having at least one opening, means for closing said opening comprising a strip folded over said opening when the opening is closed, adhesive sealing means 70 between the bag and closing means, and at least one extension from said bag formed by at least one continuous portion of said closing means and means for positively holding said closing means to the bag near the point 75 from which it forms an extension, said extension of the closing means being looped back upon itself, the end thereof also being held by said positive holding means.

2. A bag having at least one opening, means for closing said opening comprising a strip folded over said opening when the opening is closed, adhesive sealing means between the bag and closing means, and at least one extension from said bag formed by at 80 least one continuous portion of said closing means and means for positively holding said closing means to the bag near the point from which it forms an extension, said extension of the closing means being looped back upon itself, the end thereof also being held by said positive holding means, said positive holding means comprising at least one member 85 passing through the juxtaposed thickness of closure means and bag near said point of extension.

3. A bag having at least one edge, means covering said edge comprising a strip folded over the edge, means for attaching said strip to said edge, and at least one extension from the bag formed by at least one continuous portion of said strip, said extending portion being looped back upon itself, and means joining the end of the loop portion with the strip itself.

In testimony whereof, I have signed my name to this specification this 19th day of February 1931.

CHARLES V. BRADY.
